(57) **CLAIM**

The ornamental designs for a solenoid valve manifold, as shown and described.

DESCRIPTION

1.-2. Solenoid valve manifold

1.1 : Perspective

1.2 : Front

1.3 : Back

1.4 : Top

1.5 : Left

1.6 : Right

1.7 : Bottom

2.1 : Perspective

2.2 : Front

2.3 : Back

2.4 : Top

2.5 : Left

2.6 : Right

2.7 : Bottom

The broken line portions do not form part of the claimed designs.
